DESIGN FOR A BELT

William F. Cox, Dallas, Tex.

Application June 17, 1946, Serial No. 130,800

Term of patent 7 years

(Cl. D3—10)

To all whom it may concern:

Be it known that I, William F. Cox, a citizen of the United States, residing at Dallas, in the county of Dallas and State of Texas, have invented a new, original, and ornamental Design for a Belt, of which the following is a specification, reference being had to the accompanying drawing, forming part thereof.

Figure 1 is a plan view of a belt showing my new design.

Figure 2 is a front elevational view, and Figure 3 is a rear perspective view thereof.

I claim:

The ornamental design for a belt, as shown.
WILLIAM F. COX.
